GARMENT LACING

Filed May 12, 1931

FIG. 1.

FIG. 2.

FIG. 3.

Oscar Weingarten

INVENTOR

BY *Oscar Weingarten*
his ATTORNEY

UNITED STATES PATENT OFFICE

OSCAR WEINGARTEN, OF NEW YORK, N. Y.

GARMENT LACING

Application filed May 12, 1931. Serial No. 536,762.

This invention relates to an improved lacing means for garments and has special reference to lacing means adapted for use as a corset lacing.

5 The present invention is an improvement of the corset lacing arrangement disclosed and patented by me in United States Letters Patent No. 1,483,702, issued February 12, 1924.

10 My invention has for its object to provide an efficient form of lacing means of extremely simple construction, in which there will exist no protruding parts to cause discomfort to the wearer, and by means of which I secure 15 ease and certainty of manipulation and greater life for the lacing cord and corset as a whole.

Briefly, the present invention comprehends all of the features of the arrangement set 20 forth in the above mentioned Letters Patent, but instead of the circular eyes formerly used, I have substituted for each of them a double loop eye, which enables the portion thereof carrying the lacing to be disposed 25 parallel and flat against the underlying surface of the garment. This arrangement is particularly desirable because in laced position there is no tendency of the eyes to assume an upright position and as a consequence to press inwardly against the wearer.

I accomplish the purpose of my invention by means of an arrangement of parts herein-after described in the specification, set forth in the claims and illustratively exemplified in 30 the accompanying drawings, in which Figure 1 is a fragmentary elevational view of a corset provided with my improved lacing arrangement; Figure 2 is an elevational view of the strip of material to which the lace receiving members are attached; and Figure 3 is a substantially transverse sectional view taken on lines 3—3 of Figure 1.

Referring now to the drawings, A and B represent the halves of an ordinary corset. 45 Each half of the corset is built up of the usual fabric covering 10 with interposed stays 11 spaced apart over the garment. The halves each terminate along their ends in an edge 12 which is free and loosely supported 50 along one set of stays 11, as illustrated par-

ticularly in Figures 1 and 3. An eyelet carrying tape 13 is disposed over the stay 11 adjacent each edge 12 and is stitched to the body of the corset by parallel rows of stitching 14 engaging along the sides of a facing strip 15 and interposed tape 13.

The tape 13 is provided to support the staples 16 of the movable lace receiving members 17. The closed ends of the staples 16 project outwardly onto the edges 12 from beneath the facing tapes 15 and in each instance they carry a double loop eye 18, one loop being smaller than the other and turned at right angles thereto so that when the smaller loop encircles its staple 16 the larger 65 loop takes its position against and parallel to the edge 12. In this manner the lacing 19 passing through the larger loops also fits flatly against the edges 12 thus avoiding any raised portions to press against the wearer. 70

The manipulation of a lacing device of the character just described is extremely simple. To tighten the corset it is simply necessary to draw outwardly on the ends of the lacing cord 19, and owing to the construction and arrangement of the double loop eyes 18 the 75 corset edges 12 will be smoothly and uniformly drawn together, without the need for pulling with the fingers at any intermediate parts of the cord. The cord after completing the tightening operation is secured by tying the ends together. To release the cord the knot is untied and the pressure on the halves A and B will cause the latter to spread as the lacing runs without resistance through 80 the larger loops of the eyes 18. The substantially universally mounted eyes 18 insure ease not only in the tightening operation of the 85 corset but in the removal operation as well. Furthermore, the mounting of each eye 18 90 according to the present invention prevents any part of the loop from protruding and engaging the wearer, since the lace receiving loop is always disposed parallel with the face of the corset edges 12.

Having described my invention and the manner in which the same is used, what I claim and desire to secure by Letters Patent is:—

1. In a garment of the character described, 100

- the combination with the edge portions of an opening in said garment, of lacing means secured to said portions at spaced intervals, said means comprising a series of staples, and lace receiving members carried by the staples, each member comprising a double loop forming a small opening and a larger opening, the loop forming the small opening being looped about the respective staple and the loop forming the larger opening being adapted to receive the lacing therethrough, the loops of each member being bent to bring the larger loop at such an angle to the smaller loop as to enable the larger loop to lie parallel with the surface of the edge of the garment.
2. In a garment of the character described, the combination with the edge portions of an opening in said garment, of lacing means secured to said portions at spaced intervals and disposed back of the free extremities of said edge portions, said means comprising a series of staples, and a series of double orificed lace receiving members mounted on the staples, each member having its orifices disposed at an angle to the other, the member being linked in a staple at one end and the portion of the member at the other end being disposed to lie flat against an edge portion of the garment.
3. Lacing means for garments as claimed in claim 2, in which the orifice in the end of the member receiving support in the staple is smaller than the other end, the smaller orifice being sufficient to permit the member to have substantially universal movement with respect to the staple.

In testimony whereof I affix my signature.
OSCAR WEINGARTEN.
